UNITED STATES PATENT OFFICE

WILLIAM GENTRY SHELTON, OF ST. LOUIS, MISSOURI

HAIR WAVING DEVICE

Application filed October 9, 1931. Serial No. 567,823.

This invention relates to hair waving apparatus and particularly to curling rods of the type used in making so-called croquignole permanent waves.

5 One object is to produce regular waves of the croquignole type by winding from the scalp outwardly.

Another object of the invention is to provide a curling member including an outer sleeve-like element having staggered prongs for receiving the wound strand, and also having a separate inner element yieldingly held within the outer sleeve member, preferably by frictional engagement therewith, 15 and rotatable therein for the purpose of tightening the wound strand.

Another object is to provide a curling rod which will make the curls smoother and more regular than similar devices previously in use.

Another object is to make croquignole waves with simpler and less expensive apparatus than previously required.

These and other more detailed objects are 25 attained in the structures illustrated in the accompanying drawing in which—

Figure 1 is a view of the curling device with a strand of hair wound thereupon.

Figure 2 is a similar view of the curling 30 rod alone.

Figure 3 is a longitudinal section taken on line 3—3 of Figure 2.

Figure 4 is a view of the inner rod before insertion into the outer sleeve member and 35 showing the ultimate position of the outer member in broken lines.

Figures 5 and 6 are sectional views taken on the corresponding section lines of Figure 2.

The invention comprises an outer sleeve 40 member 1 having prongs 2 projecting therefrom, and an inner rod member 3. Prongs 2, preferably, project from member 1 at regular staggered intervals and are disposed in rows on opposite sides of the member. Protruding cap elements 4 are provided on the ends of the prongs 2 for preventing the wound hair strand S from slipping off from the curler.

50 As particularly illustrated in Figures 5 and 6, the outer peripheries of the cross sec-

tions of prongs 2 and the elongated central portion 1 are of the same size and shape and the prongs are equally spaced apart so that the finished wave will be smooth and regular as each crimp will be made over a rod section 55 of the same size and shape as every other crimp forming section.

In Figures 3 and 4, the distortion of the inner rod 3 with relation to the outer member is clearly shown. Rod 3 is normally bent as in Figure 4, and is slightly straightened in insertion into member 1. The frictional engagement of members 1 and 3 yieldingly resists relative rotation thereof so that, while rod 3 may be turned manually to tighten or release the wave, the rod will be prevented from any turning due to tension on the wound strand.

The tightening rod projects beyond the ends of the outer member and has a longitudinal slot 8 in one end for receiving a cord 9 which provides for attachment to the rod of a portion of the strand adjacent the scalp. The rod 3 is flattened at the outer end to provide a handle 6. Member 1 has a smooth 70 sleeve 10 extending along the rod a short distance from the outer end thereof for receiving the unwound portion of the hair strand. A suitable cord or band 11 is provided for securing the end of the hair strand to sleeve 75 10.

The prongs 2 are illustrated as solid in Figure 5, but it will be understood that the entire outer member may be made of hollow metal in order to decrease the customer's discomfort due to the weight of the apparatus.

The device is comparatively simple, having only two parts and there are no delicate parts to become worn or, possibly, broken. The inner rod is shown as distorted in three 80 places in order to provide a plurality of contacts with the outer sleeve but this form of distortion is not essential and a single bend or other shaping of the rod or outer member to secure suitable frictional engagement therebetween may be substituted.

Obviously, the structure illustrated may be modified otherwise as to details without departing from the spirit of the invention and exclusive use of all such modifications as 100

come within the scope of the appended claims is contemplated.

What is claimed is:

1. A hair curling device comprising an outer sleeve-like member having prongs projecting sidewardly therefrom for receiving and curling a strand of hair, and an inner rod having an end portion projecting beyond an end of said member and arranged for attachment of a strand of hair, said rod being revolvable within said member and serving as a hair tightener.
2. A hair curling device comprising an outer sleeve-like member having prongs projecting sidewardly therefrom for receiving and curling a strand of hair, and an inner rod having portions projecting beyond each end of said member, there being a portion of said sleeve-like member projecting beyond the last prong at one end and serving to receive the unwound portion of the hair strand.
3. A hair curling device comprising an outer sleeve-like member having prongs projecting sidewardly therefrom for receiving and curling a strand of hair, and an inner rod having portions projecting beyond each end of said member, one of said portions being arranged for attachment to a strand of hair, and the other portion including a handle element, said rod being revolvable within said member and serving as a hair tightener.
4. A hair curling device comprising an outer sleeve-like member having prongs projecting sidewardly therefrom for receiving and curling a strand of hair, and an inner rod having portions projecting beyond each end of said member, one of said portions being arranged for attachment of a strand of hair, said rod and member having cooperating elements yieldingly resisting relative rotation therebetween whereby said rod serves as a hair tightener.
5. A hair curling device comprising an outer sleeve-like member having prongs projecting perpendicularly therefrom and disposed in staggered relation along said portion, and an inner rod having a portion projecting beyond the end of said member and provided with an element for attachment of a strand of hair, and an element frictionally engaging the inner surface of said member whereby relative rotation of said rod and said member is resisted and said rod serves as a hair tightener.

55 In testimony whereof I hereunto affix my signature this 6th day of October, 1931.

WILLIAM GENTRY SHELTON.
